LIGHTING FIXTURE

Application filed February 25, 1927. Serial No. 170,844.

The present invention relates to lighting fixtures, and is more particularly directed toward an indirect lighting fixture of the type in which an opaque deflector surrounding the light source is used for the purpose of reflecting light onto the ceiling.

The present invention contemplates a fixture of this type wherein a translucent disk is carried underneath the light source and is 10 so arranged that the disk acts on a portion of the light to reflect it onto the outside surface of the deflector so as to illuminate it. According to a preferable embodiment of the present invention, this disk is supported by a 15 perforate stamping which surrounds the deflector and is supported from the upper edge of the deflector. The light coming from the outside of the deflector passes through the perforations in the stamping so that these 20 perforations stand out in bold relief. The deflector may have contrasting color so as to bring out the design in a striking manner.

According to the present invention, the deflector is preferably rigidly mounted in its 25 support and the glass disk and perforate stamping are removably carried from the upper edge of the deflector.

Other and further objects of the invention will be apparent as the description proceeds.

30 The accompanying drawing shows, for purposes of illustrating the invention, one of the many possible embodiments in which the invention may take form, it being understood that the drawings are illustrative of the invention rather than limiting the same.

In these drawings:

Figure 1 is an elevational view of the lighting fixture, and

40 Figure 2 is a fragmentary top plan view of the peripheral portion of the lighting fixture.

A downwardly opening lamp socket 10 is supported in any suitable manner at the lower end of a fixture supporting stem 11. The socket carries a lamp 12 and the lamp socket 45 and neck of the lamp bulb are surrounded by a socket cover 13. A number of arms 14 are attached to the lower end of the socket cover and extend downwardly and outwardly below the lamp as indicated. These arms are 50 secured in the lower end of the socket cover

by screws 15. The lower ends of the arms are provided with upwardly bent hooks 16. An opaque deflector 17 preferably in the form of a sheet metal stamping is carried in the hooks 16 on the arms. The lower edge of the deflector is turned back on itself as indicated at 18 and is clamped in the hooks 16 by screws 19 threaded through the arms and against the deflector. In this manner the deflector is securely carried in the lower ends of the arms 55 and will not tilt out of place.

A perforate stamping 20 surrounds the outside of the deflector 17. The upper part of the stamping comes close to the upper edge of the deflector as indicated at 21 and then extends outwardly and upwardly as indicated at 22. A plurality of supporting members 23 are fastened to the stamping 20 and are arranged so as to extend over onto the upper edge of the deflector 17. These members are 60 preferably pivoted about a rivet, such as indicated at 24, and have an upwardly extending finger piece 25 to facilitate turning them about the pivot. The portion of the stamping 20 which is directly outside the deflector 17 is preferably provided with perforations 65 such for example as indicated at 26, these perforations being of any ornamental design desired.

The lower portion of the stamping 20 is inwardly directed as indicated at 27 and a translucent glass disk 28 is carried in an opening in the stamping 20. This translucent disk will transmit considerable light downwardly to provide illumination directly underneath the fixture. Some of the light, however, will be reflected upwardly by the glass disk and will pass between the disk and the lower edge of the deflector and will fall upon the outer curved surface. This illuminated 70 surface will be visible through the perforations 26 in the stamping 20. If desired, the glass disk may carry an ornamental tassel which is indicated at 29.

It will be noted that the glass disk is supported from the upper edge of the deflector by means of a stamping 20 and that the stamping and the disk may be lowered by turning the members 23 sufficiently to permit the stamping 20 to swing downwardly free of the 75 100

deflector. Where three such members are used, one may, if desired, permanently rivet two of these members to the outer stamping and pivotally mount only the third member 5 and when this third member is swung out of position, as indicated in dotted lines in Figure 2, the perforate stamping and glass disk may be allowed to swing downwardly on the outer two supporting members as pivots. During this swinging movement of the stamping and glass disk the deflector will be eccentrically loaded but it is not able to tilt about the lower ends of the adjacent hooks because of the clamping means provided by 10 the screws 19. This will permit renewing the lamp. Of course it will be understood that these parts may be readily removed from the fixtures for cleaning and lamp renewal, if desired.

20 It is obvious that the invention may be embodied in many forms and constructions within the scope of the claims, and I wish it to be understood that the particular form shown is but one of the many forms. Various 25 modifications and changes being possible, I do not otherwise limit myself in any way with respect thereto.

What is claimed is:

1. A lighting fixture having a light source, 30 a deflector for redirecting horizontally emitted light toward the ceiling, means for supporting the deflector, a translucent disk underneath the light source, the peripheral portions of the disk acting to reflect light 35 onto the outside of the deflector, and means to support the disk from the upper edge of the deflector, said means comprising a perforate stamping outside the deflector and through which light emitted from the outside 40 of the deflector may pass.

2. A lighting fixture having a light source, a deflector for redirecting horizontally emitted light toward the ceiling, means for supporting the deflector, a translucent disk 45 underneath the light source, the peripheral portions of the disk acting to reflect light onto the outside of the deflector, a perforate stamping outside the deflector removably supported from the top of the deflector and carrying the disk, the deflector being visible 50 through the perforations.

3. A lighting fixture comprising a downwardly opening lamp socket, a lamp in the socket, a socket cover, a plurality of downwardly and outwardly extending arms carried by the socket cover, upwardly extending hooks at the lower ends of the arms, an outwardly and upwardly extending deflector supported in the hooks, the deflector being 55 capable of tilting about said hooks as centers, and clamping means for securing the deflector in the hooks to prevent said tilting.

4. A lighting fixture comprising a downwardly opening lamp socket, a lamp in the socket, a socket cover, a plurality of down-

wardly and outwardly extending arms carried by the socket cover, upwardly extending hooks at the lower ends of the arms, an outwardly and upwardly extending deflector supported in the hooks, the deflector being 70 capable of tilting about said hooks as centers, clamping means for securing the deflector in the hooks to prevent said tilting, a perforate sheet metal stamping surrounding the deflector and means for supporting the stamping 75 from the upper edge of the deflector, said means permitting the stamping to be swung downwardly to hang from one edge of the deflector.

5. A lighting fixture comprising a downwardly opening lamp socket, a lamp in the socket, a socket cover, a plurality of downwardly and outwardly extending arms carried by the socket cover, upwardly extending hooks at the lower ends of the arms, an outwardly and upwardly extending deflector supported in the hooks, the deflector being 80 capable of tilting about said hooks as centers, clamping means for securing the deflector in the hooks, to prevent said tilting, a perforate sheet metal stamping surrounding the deflector 85 means for supporting the stamping from the upper edge of the deflector, said means permitting the stamping to be swung downwardly to hang from one edge of the deflector, and a translucent glass disk underneath the lamp and acting to reflect light onto the outside of the deflector.

6. A lighting fixture comprising a downwardly opening lamp socket, a lamp in the socket, a socket cover, a plurality of downwardly and outwardly extending arms carried by the socket cover, upwardly extending hooks at the lower ends of the arms, an outwardly and upwardly extending deflector 90 supported in the hooks, the deflector being capable of tilting about said hooks as centers, clamping means for securing the deflector in the hooks to prevent said tilting, a translucent 95 glass disk underneath the lamp and acting to reflect light onto the outside of the deflector, and a disk support in the form of a perforate stamping surrounding the outside of the deflector and supported from the upper edge thereof.

Signed at Meriden, in the county of New Haven and State of Connecticut, this 11th day of February, 1927.

LEROY C. DOANE.
